CLAIM

The ornamental design for a blister pack, as shown and described.

DESCRIPTION

FIG. 1 is a front perspective a top view of a blister pack showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dot-dash broken lines in the drawings define the boundaries of the claimed design and form no part thereof. The remaining dashed broken lines in the figures illustrate portions of the blister pack that form no part of the claimed design.
